CLAIM

The ornamental design for an adjustable desk lamp, as shown and described.

DESCRIPTION

FIG. 1 is a side view of the adjustable desk lamp in a typical position. The other side is a mirror image.

FIG. 2 is a frontal view of the adjustable desk lamp.

FIG. 3 is a rear view of the adjustable desk lamp

FIG. 4 is a view from directly above the adjustable desk lamp

FIG. 5 is a view from directly underneath the adjustable desk lamp

FIG. 6 is a perspective view of the adjustable desk lamp from above; and,

FIG. 7 is a perspective view of the adjustable desk lamp from below.

The broken-line disclosure is understood to represent unclaimed portions of the adjustable desk lamp.
